UNITED STATES PATENT OFFICE

CLAIR D. LAKE, OF BINGHAMTON, AND GEORGE F. DALY, OF JOHNSON CITY, NEW YORK, ASSIGNORS TO THE TABULATING MACHINE COMPANY, OF ENDICOTT, NEW YORK, A CORPORATION OF NEW JERSEY

CARD REPRODUCING MACHINE

Application filed October 27, 1930. Serial No. 491,384.

The present invention is directed to improvements in card punching apparatus.

In the tabulating machine art it is the common practice to punch cards with perforations which designate various kinds of statistical data. These cards are then utilized in sorting and tabulating machines to obtain various classified records of the data on the cards. In the use of such systems it becomes necessary from time to time to duplicate comparatively large groups of cards.

The cards themselves have been improved as regards the configuration of the perforations employed and the spacing between adjacent columns has been reduced to permit a greater amount of information to be punched in a single card. It has therefore become desirable to transfer the information contained on the old type of card to the new so that the data may be sorted and tabulated on machines designed to operate under control of the new type of card.

Such duplications if performed by hand punching would be time consuming, expensive and difficult. Furthermore, copied cards which depend upon the operator's reading the previously punched card are subject to errors.

In making such duplicated cards it is sometimes desirable to suppress a part of the data derived from the original punched card and in other cases it is desirable to arrange the punched data on the new cards in different fields and columns than that of the original cards.

It is further desirable to provide for automatically effecting punching of certain repetition data on the new cards and for disposing such repetition data in any desired fields or columns thereof.

The present invention is directed to the provision of a punching machine and a remote, independent sensing machine, in which groups of blank and punched cards may be placed respectively, and which when in operation automatically feed blank and punched cards step by step therethrough, the sensing machine reading the punchings of the punched cards and effecting a corresponding punching of the blank cards.

Provision is made for permitting the suppression of punching of desired data derived from the punched cards and provision is also made for permitting the transposing of data derived from a given field or column upon the punched cards to other fields or columns upon the blank cards. 55

Another object is to provide a card reproducing system in which a punching machine is remotely controlled by a card sensing machine and in which both machines have separate driving mechanism which need not be synchronous in their operation. 60

Another object is to provide a punching machine adapted to be controlled by a remote card sensing machine and in which keys are provided with which additional data may be punched in the card at the will of the operator. 65

Another object is to provide a card reproducing system in which a punching machine is remotely controlled by a card sensing machine and interlocking connections are provided so that feeding of a punched card to position is accompanied by a corresponding feeding of a blank card and in which feeding of one is suppressed until sensing or punching operations upon the other have been concluded. 70 75

Another object is to provide a card reproducing system having a punching machine in which blank cards may be hand punched wholly or in part. 80

Various other objects and advantages of my invention will be obvious from the following particular description of one form of mechanism embodying the invention or from an inspection of the accompanying drawing; and the invention also constitutes certain new and novel features of construction and combination of parts hereinafter set forth and claimed. 85 90

In the drawings:

Fig. 1 is a plan view of the machine comprising the card reproducing system. 95

Card feeding mechanism

The card feeding mechanism is the same for both the sensing and punching machines and it will be understood in the following description of the operation of the punching machine feeding mechanism that similar parts in the sensing machine perform similar functions.

Cards are fed from supply hoppers 10 and 10a (Fig. 1) by picker knives 11 and 11a which advance the cards to present their first columns to punching and sensing positions respectively. In this position card carriages comprising pushers 12 and 12a and forward guides 13 and 13a (Figs. 3 and 10) engage the cards and advance them step by step under control of escapement mechanism to be described later.

Pusher 12 and guide 13 are carried by an escapement rack 14 and picker knife 11 is carried by a rack bar 15 (see also Fig. 2). Rack 14 has a gear 16 meshing with its lower edge and bar 15 has a gear 17 meshing with its upper edge, both gears being mounted upon a cross shaft 18. Due to this connection between the elements, movement of picker 11 toward the left as viewed in Fig. 1 is accompanied by movement to the right of pusher 12 and this action will deliver a card from

the bottom of hopper 10 to punching position where pusher 12 engages it and further advance will be under control of the escapement mechanism. A one-way clutch mechanism generally designated at 19 in Fig. 2 permits the immediate return to the left of bar 15 and picker 11. Escapement rack 14a of the sensing machine is similarly geared to bar 15a and related parts are similarly numbered with the letter "a" suffixed.

The operation of card feeding just outlined is more fully explained in Patent No. 1,772,186 to F. L. Lee, et al, for a Duplicating punching machine and needs no further description here. The escapement mechanism referred to is of the same general nature as that disclosed in the Schaaff Patent No. 1,426,223 and a brief description thereof will be given later.

Secured to the underside of the base of each machine is a motor 20 (Figs. 2 and 3) coupled to a stub-shaft 21 to which is secured a worm 22 in mesh with a worm wheel 23 secured to a shaft 24 one end of which has secured thereto a ratchet shaped clutch element 25. Loosely mounted on shaft 24 is a gear 26 meshing with teeth on the lower edge of rack bar 15 and on which gear is mounted a disk 27. Pivoted at 28 to disk 27 is an arm 29 having a clutch tooth 30. The free end of arm 29 is connected to a toggle plate 31 by a link 32, the end of toggle plate 31 distant from its pivot 33 being articulated at 34 to a rod 35. The rod 35 is spring impelled and fits in an aperture in a pin 36 rotatably mounted on disk 27.

For the purpose of effecting a clutching action a magnet 37 is provided and when energized attracts an armature 38 so that arm 39 engaging a pin 40 of arm 29 will rock the tooth 30 into engagement with ratchet wheel 25. Through link 32 the toggle connection will be moved centrifugally, the spring on rod 35 acting to hold clutch tooth 30 in engagement with the ratchet teeth. Gear 26 will thereupon be driven in a counterclockwise direction substantially a single revolution shifting rack bar 15 to the left to feed a card from the supply hopper. This will result as premised before in the movement of pusher 12 to the right to engage the newly fed card.

At the termination of the counterclockwise movement of gear 26, a tail 41 of arm 29 will strike a projection 42 of a fixed plate to effect the disengagement of the tooth 30 and ratchet 25 by a reverse action. Gear 26 and rack bar 15 are returned to the position of Fig. 2 through a gear 43 connected to a spring barrel (not shown). The one-way clutch 19 permits such action without affecting the escapement rack 14.

Also secured to the pivot of armature 38 is an arm 44 (Fig. 3) the free end of which is adapted to bear upon an insulating block to open contacts 45 and close contacts 46 when

magnet 37 is energized. The contacts are maintained in shifted position by a latching bell crank 47, a lug of which is adapted to be engaged by a bent up plate 48 secured to gear 26, at the termination of the driving movement of the latter.

Automatic card ejector

Means are provided in both machines for automatically removing completely sensed and punched cards and depositing the same in receptacles provided for the purpose. This invention is described in detail in the application of J. M. Cunningham, Serial No. 390,755, filed September 6, 1919 to which application recourse may be had for details of construction and operation.

Stated generally the gripper (Fig. 8) comprises a pair of jaws 50 and 51 urged together by a flat spring 52 but the abutment of a pin 53 with the upper jaw 50 separates the jaws in order that the punched card (or sensed card) may be received by the slit-like separation. The card occupies a position between the jaws at the termination of the punching or sensing of the last columns of the card.

The gripper is pivotally mounted on a shaft 54 to which is secured a gear 55 adapted to be driven by a gear 56 through an idler gear. Meshing with gear 56 is a slidably mounted rack 57 the extremity of which terminates in an adjustable cylindrical plunger 58. During the previous restoration of the card carriage the end of rack 15 (Fig. 9) engaged plunger 58 to shift rack 57 to the left against the tension of a spring 59. This caused a clockwise movement of shaft 54 through the train of gears 56-55 to bring the gripper unit to the position shown in Fig. 8 whereupon a latch lever 60 engaged a shoulder 61 of the lower jaw 51. Incidentally a certain amount of compression was stored up in spring 59. Shifting of latch 60 is effected by energization of the magnet 62 which attracts its armature 63 when the magnet is energized. This causes a shifting movement of a link 64 to the right and by means of a cam shoulder 65 and arm 66 secured to the pivot shaft of latch 60 will rock the latter.

This will result in the release of spring 59 to cause the counterclockwise rotation of the gripper unit. As the jaw 50 leaves pin 53 spring 52 will act to close upon the lower jaw 51 thus securely gripping the card and flipping the same in reversed position. A stationary pin 67 may suitably coat with one of the jaws to separate them permitting the released card to fall into a receptacle 68. As the card is ejected shifting of rack 57 by spring 59 will cause a square shoulder 69 (Fig. 9) to engage and close a contact 70 and in the sensing machine contact 70a.

Card sensing mechanism

Referring to Fig. 10 the perforated card is

in position between guide 13a and pusher 12a and is adapted to move step by step past a series of sensing brushes 71 of which there are thirteen adapted to bear against an insulated conducting bar 72. The brushes 71 are carried by an insulating brush holder 73 secured between a pair of side plates of a yoke or bail shaped member 74. Each side plate is suspended at its upper end by a link 75 pivoted to the frame portion 76 and at their lower ends the side plates are supported by means of parallel links 77. Intermediate each side plate of bail 74 and related link 77 is a toggle plate linkage member 78 which is pivoted upon a rod 79. The ends of links 77 distant from their connecting points to the toggle plate 78 are pivotally secured to a pivoted armature structure 80. The armature 80 is attracted against the tension of its spring when magnet 81 is energized at which time the counterclockwise rocking of toggle plate 78 will be effective to elevate frame 74 resulting in the contact of the individual sensing brushes 71 with the common bar 72. Rocking of armature 80 also causes opening of a pair of contacts 82. Brushes 71 are adapted for continuous sliding contact with associated springs 83 which are wired to the punch selecting mechanism of the punching machine. Thus the brushes 71 are out of engagement with bar 72 except at such times as magnet 81 is energized. Twelve of the brushes make contact with the bar through perforations in the card and the other is located beyond the lateral edge of the card and serves to supply current to the bar when raised.

Sensing machine escapement

In a manner to be explained in connection with the wiring diagram magnet 84 is energized to operate the step by step escapement of the sensing machine card carriage. Upon energization of magnet 84, its armature 85 will be rocked about its pivot in a clockwise direction and through a screw stud in an arm 86 secured to rod 87 will rock the rod counterclockwise against the tension of a spring 88. Rod 87 is rocked as an incident to each spacing operation and has secured at one end oppositely extending arms 89 and 90 (see also Fig. 10a) of which 89 is provided with a laterally extending pin 89a for engagement with an enlarged opening in a stepping dog 91 which is loosely pivoted on rod 87. The opposite arm 90 is provided with a pin 90a extending in a slot formed in the locking dog 92 between its pivot and its engaging end. When rod 87 is rocked, arm 89 will, through pin 89a, lift the stepping dog 91 out of one of the notches in the rack 14a and at the same time arm 90 will depress locking dog 92 into a notch between the rack teeth. At this time a spring 93 advances the loosely pivoted dog 91 a short distance but sufficient to permit this dog to move

above the top of the next tooth. When the locking dog is again raised, the stepping dog 91, due to the movement of rack 14a will ride down along the next tooth until it strikes the end thereof and the carriage is thereby arrested. The usual spring drum (not shown) is provided to bias the rack 14a toward the left as viewed in Fig. 10.

Punching machine escapement

The escapement mechanism of the punching machine (Fig. 6) is similar to that just described, comprising a stepping dog 94, a locking dog 95 and an operating arm 96 mounted on a rod 97. The rod 97 is rocked to escape rack 14 one tooth as an incident to a punching operation in a manner presently to be described.

Operation of the punching machine

In Fig. 3 the punches 100 are of rectangular cross-section and mounted in a manner disclosed in the Patent 1,772,186, issued to F. L. Lee et al., dated August 5, 1930, and are normally held in raised position by springs 101. Resting on the upper ends of said punches are interposers 102 supported at their rear ends on a cross member 103. The interposers 102 are so notched at their forward ends that when they are in normal position as shown depression of an actuating plate 104 against a spring 105 will move a portion 106 of the plate into such notches.

However, when any numeral magnet 107 is energized under control of the sensing brushes 71 it will actuate its armature 108 to depress the corresponding key 109 which in turn will actuate a bell crank 110 against the action of a suitably connected spring. The upright arm of each bell crank 110 has a pin and slot connection with an interposer 102. Such interposer will then be advanced to such a position that depression of the member 104 will effect depression of the interposer and consequently of the corresponding punch.

Upon movement of any of the interposers 102 a pair of contacts 111 are adapted to be closed thereby closing the circuit to the punch magnet 112 which through intermediate mechanism is adapted to rock the depressor plate 104 to actuate the selected punch 100. Subsequently the circuit of the magnet 112 will be broken allowing the return of the depressed interposer to normal position.

Upon energization of punch magnet 112 in this manner its armature 113 (see also Fig. 2) will be swung about its pivot and through link 114 will rock a bell crank 115 to draw downward the link 116 and rock plate 104. Depression of any interposer 102 will, through incidental depression of bail 117, rock rod 97 to render the escapement mechanism effective and the rack 14 and the card carriage will advance one tooth to permit punching in the next column of the card.

Across the lower edge of all the interposers is a pivoted bail 118 reaching into notches in the interposers. Attached to the bail is a depending finger 119 held against a bracket 120 on link 114 by a suitable spring 121. This spring also tends to pull link 119 downwardly rocking bail 118 clockwise into engagement with the right hand shoulders of the notches in the interposers. Link 119 has a shoulder near its free end normally hooked under the lower blade of contact 111. When an interposer 102 is advanced to operative position the bail 118 is rocked counterclockwise, raising link 119 and causing contacts 111 to be closed. As the punch passes through the card and link 114 moves to the right the bracket 120 will push the link 119 to the right so that the lower contact leaf will be released and contacts 111 will then open. It will be recognized that when the lower contact leaf is released contacts 111 cannot be closed again until the magnet 107 which effected their closing has been deenergized and the next punching operation effected.

Operation of any punch may also be effected by manual depression of any key 109 corresponding to such punch. A contact 116a located at the lower extremity of link 116 is adapted to be closed by the link upon each operation of the same.

Operation of the duplicator

The operation of the punches 100 may also be controlled by means of the duplicator which causes the selector magnets 107 to be actuated in accordance with the perforations of a previously punched master card. Each of the magnets 107 is electrically connected to a related spring contact plate 122 (Fig. 4) a series of which is carried by an insulating block. Each spring 122 is adapted for a sliding continuous electrical contact with an associated brush 123 which is adapted to bear against a metal cylinder 124. The brushes 123 are mounted in a manner similar to brushes 71 (Fig. 10) and are similarly moved upwardly into cooperation with roller 124 whenever magnet 125 is energized. A contact 126 is adapted to be opened by armature 127 when the latter is attracted by the magnet.

The master card is placed in position between arms 128 (see also Fig. 1) attached to and extending from escapement rack 14 so that the master card will advance step by step with the new card being prepared. Closure of a door 129 causes closure of a pair of contacts 130 and a spring pressed latch 131 will hold the door shut. For further details of the construction and operation of the duplicator reference may be had to the application of F. L. Lee, Serial No. 307,819, filed September 24, 1928.

Column cut-out bar contacts

The machine has provision in the form of a

- notched bar for cutting out reproducing operations. A contact controlled by this bar permits reproducing only when it is closed. The bar 132 (Figs. 1, 5 and 12) is removably mounted on the bed of the master card frame and has cut out portions 133a co-extensive with the columns or fields to be reproduced by the card in the sensing machine. Cam portions 133 function to cut off the current to the sensing brushes 71 while the new card is in position to receive punching under control of the master card or manual keys 109. A spring-pressed lever 128a is pivoted upon one arm 128 attached to escapement rack 14 and has a depending projection 134 moving with the rack between bar 132 and a universal rod 135 pivoted at 136. As the rack escapes, the cam portions 133 will urge projection 134 against bail 135 rocking it so that a depending finger 137 will cooperate with a pair of contacts, opening contact 138 and closing contact 139.

Skip bar

- The punching machine is provided with the usual skip bar 140 (Figs. 3, 6, 11 and 13) removably mounted upon escapement rack 14 and provided with suitable notches and cam surfaces which cooperate with the usual skip lifter arm 141 which has a beveled end 142. In a well known manner depression of the usual skip key which is the "X" or "11" index point position key, the lifter arm is moved to the left as viewed in Fig. 11 so that the beveled end thereof cooperates with the cam surface of bar 140 to raise the end of the lifter.

The end of the lifter lies under stepping dog 94 and upon being so raised elevates the dog to release the rack 14. Lifter arm 140 will drop into the next notch in bar 14 and dog 94 will interrupt further movement of the rack beyond such point. The function of this skip bar 140 is to skip over the columns or fields which are not to be punched.

The sensing machine is provided with a similar skip bar 143 (Fig. 14) mounted on rack 14a. A lifter arm 144 (Fig. 11) cooperates with the bar to raise the stepping dog 91 of the sensing machine escapement. Arm 144 is mounted for vertical movement of its left end, and is arranged to be raised directly by the cam surfaces of the bar to elevate the stepping dog 91 and to permit engagement of the dog with rack 14a only when the arm cooperates with a notch. The function of this bar 143 is to skip over all columns or fields on a card which it is not desired to duplicate.

Miscellaneous contacts

In Fig. 6, punching machine rack 14 carries a plate 145 adapted to engage and rock a lever 146 pivoted upon a fixed member of the machine when the last column of the card is

in punching position. This lever, when so rocked will open contacts 147 and close contacts 148, 149 and 150 (Fig. 7). The sensing machine has a similar set of contacts identified in the circuit diagram as 147a, 148a, and 150a.

In both machines the raising of stepping dogs 94 and 91 will rock a member 151, loosely pivoted on rods 87 and 97 and having a lateral projection resting on the upper edges of the dogs 91 and 94. Rocking of the member will open contacts 152 and 153 in the respective machines.

In Figs. 1, 3, and 5 the card guide 13 is provided with a vertical finger 154 of insulating material which when the new card is in position to receive punching in the first column, will abut and close a pair of contacts 155.

The space key 109a (Fig. 2) is adapted to effect an operation of the escapement mechanism to advance the card one step in a known manner. In addition a pin 156 in the shank of the key will close a pair of contacts 157.

Release keys 158 and 158a are also provided in the punching and sensing machines respectively which in known manner effect mechanical release of their card carriage escapements to permit rapid advance to last column position.

Operation of the machine

The operation will now be explained in connection with a specific example to bring out the various steps involved in the automatic reproduction of a group of cards.

A new card hereinafter called the 80 column card is to be perforated under control of a previously punched card identified as the 45 column card. Other data will also be punched in the 80 column card from an 80 column master card. In Fig. 15 is shown a 45 column card certain of the data on which are to be reproduced in 80 column form as in Fig. 16. Examination of these two cards will show that the "month", "date", "year", "agency", "serial No.", "selling price", "consigned value", and "stock" are reproduced in fields of the same capacity that is fields employing the same number of columns as in the 45 column card. The "code No." field has a greater capacity and this data is derived from the "master card" as is also the data in the "order number" field and the "X" perforation in "credit" field.

To obtain the desired spacing, skip bar of Fig. 14 is cut to prevent reading of the columns of the 45 column card corresponding to the camming sections of the skip bar. Thus columns 1-10, 20-23, and 40-44, inclusive, are to be skipped and not read by the sensing brushes.

Skip bar 140 (Fig. 13) is notched to skip columns 1-35 and 71-74 inclusive and conse-

quently no punching will take place in these columns.

Cut out bar 132 (Fig. 12) is notched in this case to agree with the skip bar 140 to open 5 the circuits to the duplicating brushes 123 in those fields which have perforations not to be duplicated from the master card.

The master card is an 80 column card arranged with perforations in the "code No.", 10 "credit" and "order No." fields which perforations are to be duplicated in each new 80 column card.

In operation, after 45 column cards to be reproduced, and new blank 80 column cards 15 have been inserted in their respective card hoppers and the 80 column master card placed in its carriage, the machine is started by depressing the space key. Each ejector device then operates (ineffectively since no 20 cards are in ejecting position) and the automatic feeding device of each unit functions to bring one card into reading position and the other into punching position where their first columns are respectively beneath the 25 sensing brushes and punches. At this point a contact closes which energizes the "X" key magnet of the punching machine causing the "X" or skip perforation in column No. 1 of the card. This causes the skip lifter to be 30 operated and raised on the 80 column skip bar which causes the card to immediately space to the column in which reproduction punching is to commence, namely column 36. The 45 column skip bar also causes its card 35 to skip to the column at which automatic reading is to begin namely column 11.

As contact is established through a hole in column 11 of the 45 column card an impulse is transmitted to the punch selecting 40 magnet corresponding to the index point position of the hole sensed and a hole is punched in the same index point position in column 36 of the new card. Concurrently, the escapement magnets of the two machines are 45 energized and their respective escapement racks advance to present the next columns of the cards, namely the 12th and 37th columns. This operation continues until the fields 50 "month", "day", "year", and "agency" have been similarly reproduced. As the 45 column card escapes from column 19 to column 20 a rise on the 45 column skip bar causes the rack of this machine to move four columns to the left and no reading is taken from columns 55 20, 21, 22 or 23 since no current is supplied to the sensing brushes at this time. At this point reproducing stops.

As the 45 column card escapes from column 19 to 20 the 80 column card escapes from column 44 to 45 and a cam portion 133 in the cut out bar (Fig. 12) causes current to be supplied to the duplicating brushes 123 to sense the 45 column of the master card and data is punched in the "code No." field. During the 60 duplicating operations the escapement mag-

net of the sensing machine is not energized and the 45 column card remains at rest with its 24th column in line with its brushes.

As the 80 column and master cards escape from the 53rd to the 54th columns a notch 70 on the cut out bar switches the current from the duplicating brushes to the reproducing brushes and "serial No.", "selling price" and "consigned value" are reproduced column by column. At this point switching is again 75 effected by the cut out bar and a hole is punched in the "X" position in the first column of the "credit" field under control of the master card. The associated skip bar then advances the 80 column card to column 75 80 and the "order No." field is subsequently punched under control of the master card.

During this operation, the 45 column card has been advanced by its skip bar to its column 45 where it rests, awaiting the completion 85 of the duplicating operations, when current is again switched to the sensing machine and the "stock" field is punched.

After this last column punching, if the machine is set for automatic ejecting each 90 card will be ejected into its respective hopper and a pair of new cards fed into operating position and the foregoing sensing and punching operations repeated.

Circuit diagram

In Fig. 17 is shown the wiring diagram of the electric circuit of the device. The wiring of the sensing machine is shown on the upper part of the sheet and the wiring of 100 the punching machine is on the lower portion, the two sections being separated by the parallel broken lines. The connections between the two machines are indicated as individual broken lines which are collected within a 105 single cable with suitable plug terminals for ready connection or disconnection.

The mechanical operations as outlined above will now be traced in the same sequence on the diagram. Current is supplied from a 110 source through a switch 160 to lines 161 and 162. Assuming cards in position in the feed magazines, depression of space key 109a will establish a circuit as follows: from line 161, wire 163, contact 148a, wire 164, contact 149, 115 relay coil 165, resistance 166, space key contact 157, to post 167 and back to line 162. Since it is assumed both carriages are in last column position at this time contacts 148a and 149 are closed. Energization of relay coil 165 closes its points 168 and the above circuit through coil 165 continues through points 168, ejector magnet 62, wire 169 to post 167 and line 162. Branching to wire 170, 120 magnet 62a, wires 171 and 172, a parallel circuit also leads to post 167 and line 162, through contact 126, thus energizing both 125 eject magnets 62 and 62a. This operates the ejecting mechanisms but no card is ejected 128

since none is in position at this time in either unit.

At the end of the stroke of the ejector jaws contacts 70 and 70a are closed establishing 5 circuits through the trip magnets of the automatic feeding clutches as follows: line 161, contacts 148 and 70, magnet 37, contact 126 to post 167, also line 161, wire 163, contacts 148a and 70a, magnet 37a, coil 173, wire 172, 10 contact 126 to post 167 and line 162.

Energization of magnets 70 and 70a trips their respective clutch dogs into engagement with their driving ratchets and also shifts contacts 45, 46 and 46a to supply current to 15 the motors 20, 20a. Motor 20 is energized from line 161, wire 174, contact 46 (now closed) motor 20, contact 126 to post 167 and line 162. Motor 20a is energized from line 161, contact 46a (now closed) motor 20a, coil 20 173, wire 172, contact 126 to line 162. Both motors thereupon advance a card to present its first column to the sensing brushes or punches.

At the end of the feeding stroke, contacts 25 45, 46, 46a are unlatched and resume positions as shown.

A circuit may now be traced as follows: line 161, wire 174, contact 45, wire 175, contact 147, wire 176, magnet 81, contact 147a, 30 relay points 173a, wire 177, contact 138, wire 178, post 167, to line 162. Points 173a are normally closed and opened by their coil 173 during card feeding operations to prevent energization of the brush magnet 81 while 35 the feed mechanism is in operation.

The above circuit energizes magnet 81 to raise the sensing brushes into contact with the card and conductor 72. At the same time contact 155 is closed completing a circuit to 40 the "11" or "X" index point position selector magnet which punches an "X" hole in column 1 of the 80 column card and causes the skip lifter to cooperate with the skip bar to escape this card to column 36. The selection circuit follows from line 162, post 167, 45 wire 178, wire 179, contact 155, wire 180 to wire 181 corresponding to "11" thence to magnet 107 of "11" position, wire 182, contact 152, wire 175, contact 45, wire 174 to line 161. Contact 111 is thereupon mechanically closed 50 and punch magnet 112 is energized from line 161, contact 111, magnet 112, wire 183, wire 178 to post 167. A second circuit follows from line 161, contact 111, wire 185, magnet 55 84, contact 82, wire 178, to post 167. In this manner the escape magnet 84 of the sensing unit is energized with the punch magnet 112. Magnet 84 is adjusted to operate faster than magnet 112 and the circuit to both magnets 60 is broken as the contact 111 opens. Suitable condensers are provided to cut down the arcing condition at this contact.

The construction of the skip bar of the sensing machine prevents the stepping dog 65 entering the escapement rack and the rack

will consequently escape immediately upon completion of a feeding operation to present column 11 to the sensing brushes. As soon as contact 152 closes again, the columns in fields headed "month", "day", "year", and "agency" are reproduced in rapid succession. Each selecting circuit will follow from line 162, post 167, wire 178, contact 138, wire 177, contact 173a, contact 153 to common conductor 72, hole in the card, brush 71, appropriate wire 184 to the corresponding magnet 107 and back to line through contact 152 as before.

As the 45 column card advances from column 19 to 20 its skip bar escapes it to column 24. As the 80 column card advances from column 44 to 45 its cut-out bar opens contact 138 and closes contact 139 thereby disconnecting the current supply to the reproducing brushes and connecting duplicating brushes 123 so that the successive columns in the "code No." field will be punched under control of the master card. Each separate circuit follows from line 162, post 167, wire 178, contact 139, contact 130, conductor 124, hole in the card, brush 123, corresponding magnet 107 and back to line as before. Advancing from column 53 to 54, contacts 138, 139 are shifted back again and punching in fields "serial No.", "selling price", and "consigned value" takes place under control of the 45 column card as before. Magnet 125 is energized to elevate brushes 123 into reading position by a circuit from line 161, wire 174, contact 45, wire 175, contact 147, magnet 125, 90 contacts 130, 137, wire 178, back to line. After the last column of "consigned value" has been reproduced the 45 column card escapes to its 45th column and rests there while due to shifting of contacts 138, 139, "credit" 95 and "order No." are punched under control of the master card in known manner. Return of contacts 138, 139 to the position of the diagram will cause reproduction of the last column, namely "stock".

As the punching machine escapes from the 79th to 80th column contacts 147, 148, 149 and 150 are shifted from the position of the diagram. Subsequent energization of magnet 112 holds contact 152 open.

As the punch magnet is energized to punch in the 80th column, contact 116a is closed momentarily, setting up relay 165 through a shunt circuit around space key 157 to establish the starting circuit traced above. Contact 126 in series with magnet 37 and motor 20 prevents operation of these devices when the brushes 123 are against the card thus eliminating undue friction on the card while it 120 is being fed into operating position.

Operation of the machine may be continued as described until cards are exhausted. If desired, card levers and contacts may be provided to cut off automatic operation upon 130

failure of either card feeding mechanism to advance a card.

Manual punching

5 Where it is desired to enter additional data varying for each card as for instance in the "code No." field, this field is left blank on the master card and after column 44 has been automatically punched the machine will come 10 to rest. Operation of keys 109 will then enter data in this field in accordance with the keys depressed and automatic operation resumed after the field is completely punched.

15 *Switches*

Switch 190 when open causes the machine to come to rest after each card reproducing cycle of operations. It is then necessary to depress the space key to resume.

20 Switch 191 when open permits data punching in the first column of the card by suppressing operation of the skip mechanism.

Switch 192 when closed will initiate a card feeding operation immediately upon closure 25 of contacts 149 and 148a without waiting for a punching operation in the 80th column.

The punching machine may be operated as a separate unit independently of the sensing machine by opening switches 193 and 194.

30 To do this the sensing machine escapement rack must be to the extreme left holding contact 148a closed.

Closure of switch 195 will short circuit contact 139 and with contact 130 closed duplicating will take place automatically under control of the master card. Closure of 35 switch 196 at this time will energize brush magnet 125 when the last column is being sensed to keep the brush 123 against the card this circuit follows from line 161, wire 40 174, contact 45, contact 152, switch 196, contact 150 (closed as the card advances from column 79 to 80), magnet 125, contact 130, switch 195, wire 178, post 167, to line 162.

45 While there has been shown and described and pointed out the fundamental novel features of the invention as applied to a single modification, it will be understood that various omissions and substitutions and 50 changes in the form and details of the device illustrated and in its operation may be made by those skilled in the art without departing from the spirit of the invention. It is the intention therefore to be limited only 55 as indicated by the scope of the following claims:

1. In a card reproducing system, a sensing machine adapted to automatically feed a punched card step by step, and having means 60 for reading the punchings thereon, a punching machine adapted to feed a blank card step by step in increments different than the feeding of the punched card; and means controlled by the reading means for punching 65 data in said blank card to thereby duplicate

thereon the data derived from the punched cards, said reading means being adapted to effect a feeding operation of said punching machine upon each reading operation.

2. In a card reproducing system, a sensing machine adapted to receive a punched card, a punching machine adapted to receive a blank card, escapement mechanism in each machine for effecting step by step movement of the cards to effect advance of said card in unequal increments, an analyzing mechanism in said sensing machine adapted to analyze the several index point positions of a column of a card, a plurality of punches in said punching machine, means whereby said analyzing mechanism controls said punches to duplicate the perforations on punched card upon said blank card, and means for operating said escapement mechanisms together during the punching operation to feed said cards different distances. 70

3. In a card reproducing system, a sensing machine with means for automatically effecting a step by step movement of a pattern card, a punching machine with means for automatically effecting a step by step movement of a work card, the step-by-step movements of the two cards being in unequal increments, punches in said punching machine, means controlled by said pattern card for causing operation of said punches to effect a duplicate perforation in said work card, and means operative as an incident to a punching operation for effecting an automatic movement of said cards whereby each 90 95 is advanced a different amount. 100

4. In a card reproducing system, mechanism for sensing a punched card step by step, a remotely located mechanism for feeding a blank card, punches controlled by said sensing mechanism to punch duplicate holes in said blank card upon each sensing operation and means controlled by said feeding means for suppressing the operation of said sensing mechanism to prevent said duplicating 105 operation of said punches. 110

5. In a card reproducing system, mechanism for sensing the columns of a perforated pattern card, independently operated mechanism for punching the columns of a work card, means controlled by said sensing mechanism for controlling said punching mechanism to reproduce the perforations in the column of the pattern card in a different column of the work card, means controlled by 115 said feeding means for suppressing the sensing of predetermined columns of the pattern card whereby only certain predetermined columns of data are reproduced. 120

6. In a card reproducing system a card 125 sensing machine with means for feeding a perforated pattern card step by step, a punching machine with means for feeding a work card step by step independently of the movement of said pattern card, means controlled 130

by said sensing machine for punching said work card column by column in accordance with data contained in the columns of said pattern card, means for automatically skipping a predetermined column of said pattern card whereby the data in said skipped column is not reproduced and means for skipping a predetermined column of said work card independently of the movement of the pattern card whereby said skipped column is not perforated.

7. In a card reproducing system a sensing machine provided with mechanism for feeding a pattern card to sensing position, means for advancing said pattern card through the machine, and means for ejecting said pattern card; a punching machine provided with mechanism for feeding a work card to punching position, means for advancing said work card through the machine, and means for ejecting said work card; and means controlled conjointly by the positions of both said cards in their respective machines for controlling the simultaneous operation of said ejecting means.

8. In a card reproducing system a sensing machine provided with mechanism for feeding a pattern card to sensing position, means for advancing said pattern card through the machine, and means for ejecting said pattern card; a punching machine provided with mechanism for feeding a work card to punching position, means for advancing said work card through the machine, and means for ejecting said work card; and means controlled conjointly by the positions of both said cards in their respective machines for controlling the simultaneous operation of said feeding mechanism.

9. In a card reproducing system, a sensing machine provided with feeding means for feeding punched cards into and through the machine and means for reading predetermined fields of punched columns upon the punched cards; a punching machine provided with feeding means for feeding initially unpunched cards into and through the machine and having means controlled by said reading means for punching said data upon predetermined portions of the cards, and supplemental means independent of said punching in said initially punched cards and including a prepunched master card and sensing means therefor for effecting the punching of repetition data upon desired fields of the initially unpunched cards.

10. In a card duplicating machine, in combination with means for automatically and independently feeding punched and unpunched cards through the machine step by step in relatively different increments from a supply stack to a delivery stack, means for reading the punchings of the punched cards column by column during their pas-

sage from said supply stack to delivery stack, means controlled by the reading means for selecting punches for operation upon the unpunched cards, and means for displacing said selected punches through the unpunched cards to thereby duplicate thereon by punchings the data derived from the punched cards.

11. In a card reproducing system, a punching mechanism having card feeding mechanism adapted to feed a record card, a card sensing mechanism having card feeding mechanism adapted to feed a pattern card, means operated by said card sensing mechanism for concurrently controlling said record card and pattern card feeding mechanisms to feed their respective cards unlike distances, a plurality of keys, means controlled thereby for operating said first named feeding mechanism independently of said second named feeding means, and means adapted to render said second named feeding means inoperative during operation of said keys.

In testimony whereof we hereto affix our signatures.
